FUSE

Richard H. Whitehead, New Haven, Conn.

Application March 9, 1940, Serial No. 323,069

2 Claims. (Cl. 102—83)

This invention relates to time fuses. It is an object of this invention to provide for a new and improved time fuse which will overcome the difficulties at present encountered.

One of the general types of time fuses now employed comprises a gear train operated by centrifugal weights and a time disc operated by the gear train. The gear train is so constructed and arranged that when the disc is displaced from its zero position the gear train, during rotation of the shell, will return it at a fixed rate to the zero position at which position it can release the detonating charge for the shell.

The disc is connected to the nose of the fuse in some manner to permit the disc to be rotated from its zero position by the precise amount necessary to give the timing desired, but it is also necessary that this connection between the nose and the disc shall be broken as the shell is fired, so that the timing mechanism may return the disc to zero for timing purposes without the necessity of rotating the nose backward.

This invention has particularly to do with the mechanism for connecting the nose of such a fuse with the timing disc and has as an object to permit the accurate setting of the disc and at the same time to insure the complete disconnection between the disc and the nose during the firing.

It is a further object of this invention to provide a mechanism of the character described which is capable of quantity production, consistent with extreme reliability.

Other objects of the invention will in part be obvious and will in part appear hereinafter.

The invention accordingly comprises an article of manufacture possessing the features, properties and the relation of elements which will be exemplified in the article hereinafter described and the scope of the application of which will be indicated in the claims.

For a fuller understanding of the nature and objects of the invention, reference should be had to the following detailed description, taken in connection with the accompanying drawing, in which:

Fig. 1 is a vertical section through a fuse embodying this invention.

Fig. 2 is a side elevation, partly broken away, of the same.

Fig. 3 is a section on the line 3—3 of Fig. 1.

Fig. 4 is a modification.

In the drawing the numeral 10 designates the base portion of the fuse adapted to be connected to the shell, the numeral 11 designates the nose

portion, which is rotatably mounted upon the base, as shown at 12. This nose is provided with graduations 13 adapted to coordinate with an index 14. These graduations 13 are a distance 5 apart precisely corresponding to the angular distance through which the disc, hereafter to be described, is rotated by the time train during one second of movement and the graduations are preferably subdivided as is customary. The nose 10 11 is held upon the base 10 in any convenient manner, not shown, which will permit the rotary adjustment of the nose when sufficient force is applied, but which will prevent its coming off or becoming accidentally turned when not intended. This construction is common in the art and forms no part of this invention.

Within the body of the fuse there is provided a time train 15 having a disc 16 mounted upon an axial shaft 17, the time train being so constructed 20 that when the disc is in its zero position it is capable of releasing a firing pin, not shown, to detonate the shell (if the safety devices are otherwise released), but when the disc 16 is rotated from its initial position the firing pin cannot be released until the disc returns to zero. The disc is so connected to the timing train that if the shell be rapidly rotated while the disc is displaced from its zero position, the timing train itself will return the disc to its zero position at a rate of 25 speed predetermined by the time train itself, as for example by an escapement forming part of the time train. An annular guard 18 may be provided, if desired, extending over the outside of the time train 15 and extending over the edges 30 of the timing disc, as shown at 19, so that the large and complicated forces to which the disc is subjected during the firing operation may not distort the disc 16 far enough to cause any interference with the operation of the mechanism. 35 The mechanism heretofore described is characteristic of time fuses of this type and by itself forms no portion of the invention herein described.

This invention relates to the method of connecting the timing disc 16 with the nose 11. To accomplish this result there is provided upon the disc 16 a long finger 20 which preferably extends above the guard 18 and beyond its outer edge, in position to engage a pin 21 which extends downwardly from the interior of the nose 11. This engagement between the finger 20 and the pin 21 is such that as the finger 20 is bent downwardly it will disengage the pin completely and the finger 20 is constructed to carry sufficient weight so 50 that it will bend down out of engagement with

the pin under the force of the impact of the propulsive charge.

The practical manner of producing these results is as follows. A small disc 22 is mounted flat upon the disc 16 and riveted or staked thereto and this disc has an extension upon one side which itself forms finger 20. In this manner the thickness of the finger 20 and hence the ease with which it may be permanently deformed as well as the length of the finger are independent of the material and of the construction of the disc 16. Mounted upon the outer end of the finger 20 there is provided a weight 23 which is provided with a slot 24 into which the pin 21 may extend to rest upon the outer end of the finger 20 itself. Thus, by reason of the fact that the pin rests firmly against the flat surface of the finger but engages the sides of the slot in the disc, the device may be assembled with a certain initial pressure between the finger and the pin to assist in holding the pin in place. At the same time the pin itself because of its partial displacement is already partially moved toward the point of permanent distortion. Thus it does not require the degree of actual bending of the finger 20 to cause it to take a permanent set that would otherwise be the case. The weight 23 may be provided with a downwardly extending portion 25 adapted to engage the guard 18 to take the blow of the weight 23 without having that blow fall upon the extended portion 19 of the guard which is above the disc. There is thus no danger of the disc 22 being clamped by the bending of the extension 19.

It will be noted that by this construction the thickness of the metal of the finger 20 may be chosen at will and may be so selected as to give a positive and complete release under action of the propulsive charge without danger of the pin 21 being disconnected from the finger 20 during any normal handling.

This making of the finger 20 relatively thin makes it possible to employ a weight 23 of such small size that there is no danger that the rotational inertia of the weight 23 will slip the disc 16 on its bearings under the influence of the rotational accelerating force. As has been previously described, the slip connection between disc 16 and the shaft 17 is accomplished by placing above the disc and, as illustrated, above the auxiliary disc 22, a bell shaped washer 26 held in place by lock nuts 27.

It will be understood that the auxiliary disc 22 and finger 20 are made of a metal having sufficient resilience to prevent the finger from becoming disengaged with the pin 21 under severe handling conditions even under drop test, but

will be permanently disengaged by the set back of the propulsive charge. By reason of the fact that most of this resiliency is taken up in its static position, it does not require much further motion to effect its permanent distortion and thereby completely free the pin from the finger.

From the foregoing it will be seen that this invention makes possible the setting of the connecting pin 21 much further from the axis of the device so that greater accuracy in setting can be thus obtained. Moreover since the length of the finger 20 is no longer limited by the diameter of the disc 16, it is possible to construct the finger that it is more readily bent and distorted inwardly.

The construction of Fig. 4 shows a modification in which the finger 20 is bent back upon itself as shown at 30 to provide such weight as may be necessary to bend the finger and this bent back portion may be slotted as shown at 31 to receive the pin 21.

Since certain changes may be made in the above construction and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the invention which, as a matter of language, might be said to fall therebetween.

Having described my invention, what I claim as new and desire to secure by Letters Patent, is:

1. In a time fuse comprising a timing disc, mechanism for driving said disc at a predetermined rate during flight of a projectile, including a slip connection between the disc and the mechanism, a nose, a releasing mechanism comprising a pin extending downwardly from said nose, a finger extending radially outwardly from said disc and having a recess therein into which said pin extends, said finger having sufficient weight to be deformed by the set back forces to free itself completely from said pin, said recess having a bottom against which the pin may bear and the finger being under stress to hold the finger firmly against the pin.

2. A device in accordance with the preceding claim in which the finger is formed of a separate piece firmly attached to the disc and of less thickness.

RICHARD H. WHITEHEAD.
